UNITED STATES PATENT OFFICE.

HENRY DUESBERG BOSSON, OF VERVIERS, BELGIUM, ASSIGNOR TO LOUIS CLARENBACH, JR., OF PHILADELPHIA, PENNSYLVANIA.

FLEECE-DIVIDING ATTACHMENT FOR CARDING-MACHINES.

SPECIFICATION forming part of Letters Patent No. 363,200, dated May 17, 1887.

Application filed October 13, 1886. Serial No. 216,117. (No model.) Patented in Belgium July 16, 1883, No. 61,935, and in Germany August 5, 1883, No. 25,563.

To all whom it may concern:

Be it known that I, HENRY DUESBERG BOSSON, a citizen of Belgium, residing at Verviers, Belgium, have invented certain new and useful Improvements in Fleece-Dividing Attachments for Carding-Machines; and I do hereby declare the following to be a full, clear, and exact description of the invention, such as will enable others skilled in the art to which it appertains to make and use the same.

My invention relates to attachments to carding-machines, by means of which the rollers carrying the dividing-blades are vibrated. These dividing-blades receive and divide the web or fleece of wool as it comes from the condenser, and in the devices now in use they are laterally stationary and work always on the same lines or places upon the dividing-aprons. The waste, dust, or fly from the cards gathers in the spaces between the blades, and unless cleaned off is liable to enter the rubbing parts and cause irregularities in the ends, and the blades working always in the same places on the aprons eventually wear into the leather aprons, forming ridges therein, thus making said aprons practically unfit to work with any other size or number of blades. Particularly is this the case where the dust or fly is allowed to accumulate between the blades and get under them in considerable quantities at a time by accident.

The object of this invention is to obviate these difficulties and cause the dust or fly to be cleaned off regularly and thoroughly, and to gradually and regularly change the position of the blades upon the apron. This object is attained by giving to the rollers which hold the blades a slow forward-and-backward motion in the direction of their length, whereby the series of blades on both of said rollers are constantly changing their positions on the aprons. This constant change of position of the blades, by sliding over the aprons, serves to clear or clean the dust and fly from the entire surface of the aprons, and entirely overcomes the objections to the use of the stationary blades.

The following detailed description by figures and letters will more clearly and fully explain the nature and operation of my said invention.

The accompanying drawings illustrate what I consider the best means for carrying my invention into practice.

In my said drawings, Figure 1 is an end elevation of the attachment, or that portion of it which illustrates the application of my improvements, with the framing removed. Fig. 2 is a front view of the same, showing the means for reciprocating the blade-carrying rollers. Fig. 3 is a perspective view of the front of a machine having the features herein described and claimed in connection with other operative parts of the device.

Similar letters of reference indicate corresponding parts in all of the figures.

A A' are the blade-carrying rollers.

a a' are the series of blades, fastened to their respective rollers in such a manner as to cause the blades on one roller to match or register with the spaces between the blades on the other roller. The said blades are of such pliable character as to interlock or interlie with each other after leaving their respective rollers.

B B' are the dividing-aprons carried by rollers b b', respectively.

The blades a a' are bent over the abutting ends or curves of their respective aprons and held upon them by confining-rollers c c', as shown.

The construction thus far indicated by reference-letters is substantially that which is already known, and the operation of the blade-carrying rollers to produce the reciprocation of the blades in their longitudinal direction is attained by means ordinarily employed for this purpose, and may consist of the cranks o o, connected together by link o', and operated by the pitman-rod p, which is connected to crank-wheel q, which latter is driven by a train of gearing from the power-shaft r. The disk G also receives motion from the same source by means of the gear and worm s, ratchet t, and pawl u, secured upon the pin of one of the cranks o.

My invention, as already stated, consists in vibrating or reciprocating the blade-carrying rollers with a slow and even forward-and-backward movement in the direction of their length,

whereby the blades and moved over the entire exposed surface of the aprons, and do not rest thereon at any one point for a moment. The amount of movement necessary to cover the 5 entire width of the aprons by the reciprocations of the blades will, as can be readily seen, not much if any exceed the width of a single blade, and the movement, while constant, must be or, preferably is slow and regular. The 10 blades being held securely upon the aprons and in close contact therewith by the confining-rollers *c c'*, the back-and-forward movement of the blade-carrying rollers will cause the said aprons to be cleaned of all dust and 15 fly, and at the same time the aprons will not be worn in grooves, as would be the case if the blades always followed the same track. The wear being evenly distributed over the entire surface of the aprons, the width or number of 20 the blades may be changed at any time, and they will work upon the old apron with the same facility and effect as upon the new one. The reciprocation or vibration of the blade-carrying rollers may be effected in any desired 25 manner. The entire frame in which they are mounted, may be moved. I have shown the rollers with elongated gudgeons or journals, as shown at *a'*, working in boxes *d d*, which permit them to be moved longitudinally. A yoke, 30 *E*, secured upon the gudgeons in such a manner as to permit their rotation, but to control their longitudinal movements, unites the two rollers. A lever, *F*, with a slot, *f'*, for resting over crank-pin *g* on wheel *G* and fulcrumed at 35 *f*, is pivoted to a connecting-rod, *F'*, which is pivoted to the yoke *E*. By the rotation of the wheel *G* the lever *F* and link *F'* are caused to reciprocate the yoke *E*, which causes the re-

ciprocation of the rollers and the back-and-forward movement of the blades over the aprons; 40 but this mechanism for producing this result may be varied and any other construction capable of effecting the same result substituted in its place.

The character of machine to which the herein-described attachment is applicable may be seen in patent to J. S. Bolitte, No. 312,424, February 17, 1885, which shows the means for producing all the actions of the rollers and blades, except the longitudinal movement of the rollers *A A'*, which is provided for in this application. 45

Having thus described my invention, what I claim, and desire to secure by Letters Patent, is—

1. The combination of the dividing-aprons, dividing-blades, longitudinal rollers on which the blades are secured, and means for reciprocating said rollers, substantially as set forth. 55
2. The combination of the dividing-aprons, dividing-blades, and rollers for carrying the same, with means, substantially as described, for reciprocating or vibrating the blades upon the aprons, as set forth. 60
3. The combination, with the dividing-aprons, dividing-blades, and rollers on which said blades are secured, of the yoke *E*, the lever *F*, and connecting-rod *F'*, and wheel *G*, having crank-pin, all substantially as and for the purpose described. 65

In testimony whereof I affix my signature in presence of two witnesses.

H. DUESBERG BOSSON.
